SOUND REPRODUCING DIAPHRAGM

Application filed May 28, 1926, Serial No. 112,391. Renewed April 23, 1930.

This invention relates to sound reproducing diaphragms. One of the objects thereof is to provide a device of the above nature which is practical and efficient. Another object is to provide a diaphragm which is capable of giving a more natural, fuller and truer reproduction of sounds than is accomplished by sound reproducing diaphragms commonly in use. Another object is to provide a diaphragm of the above nature which is simple in construction and which may be manufactured at low cost. Other objects will be in part obvious or in part pointed out hereinafter.

15 The invention accordingly consists in the features of construction, combinations of elements, and arrangements of parts as will be exemplified in the structure to be herein-after described and the scope of the application of which will be indicated in the following claims.

In the accompanying drawings in which are shown one or more of the various possible embodiments of this invention,

20 Figure 1 is a sectional view of one form of the diaphragm associated with the stylus of a phonograph;

25 Figure 2 is a sectional view showing a modified form of the diaphragm mounted in operative relation to an electromagnet such as employed, for example, in radio loud speakers, and

30 Figure 3 is a front elevation of a portion of the diaphragm shown in Figure 2.

35 Referring now to Figure 1 of the drawings, the diaphragm shown therein is in the form of a solid disk which is preferably circular. The diaphragm is secured about its periphery in a casing 10 which represents the usual sound box of a sound reproducing machine or phonograph. Attached to the center of the diaphragm by a screw 11 passing therethrough is the usual stylus arm 12 which is pivoted to the casing at 13 and carries at its lower end the needle or stylus 14. It will be understood, of course, that the needle 14 coacts with the grooves in a rotating record, imparting vibrations to the arm 12 which in turn vibrates the diaphragm to effect reproduction of sound.

Considering now the construction of this diaphragm shown in Figure 1, it is preferably one solid member and made of a suitable resilient or flexible material such, for example, as hard rubber or the like. The central portion of the diaphragm to which the stylus arm 12 is attached is thin, and immediately about this very center of the diaphragm, it increases gradually in thickness in a radial direction to a point 15. From the point 15 outwardly, the diaphragm is made up of a series of radially spaced concentric rings 16 which are of substantial thickness and of substantial weight. These rings 16 are of greater thickness in an axial direction than is the central portion of the diaphragm. These heavy rings 16 are joined together by thin web-like rings 17.

Since each of the heavy rings is of greater diameter than the next adjacent inner ring, each of the rings 16 is of greater size and hence of greater weight than the next adjacent inner heavy ring. Thus, the heavy rings 16 increase progressively in weight from the center outwardly, each of the heavy rings constituting a member which is heavier than its neighboring heavy ring on the inner side thereof. It may be noted that the thickness of the rings 16 in an axial direction is substantially greater than the thickness of the ordinary diaphragm.

A diaphragm constructed as above described gives a fuller and richer tone than does the ordinary diaphragm. There are provided in effect, by this construction, a series of independent diaphragms each of which is best suited to vibrate for the reproduction of sounds contained within a certain range of pitch. For example, the notes of very highest pitch do not require the vibration of a large or heavy body for their proper reproduction and hence they may be reproduced by vibrations of the thin central portion of this diaphragm. The notes of next lowest pitch may be reproduced by vibration only of the portion of the diaphragm taking in the thin central portion and the first heavy ring 16. The notes of next lower pitch may be reproduced by vibration of that portion of the diaphragm

taking in the thin central portion and the first two heavy rings 16, and so on, the notes of lowest pitch being reproduced by vibrations of the entire diaphragm. The thin web-like rings 17 connecting the heavier rings 16 permit this vibration of different portions of the diaphragm best suited to reproduce the sounds being dealt with.

In Figure 2 there is shown a modified form 10 of this diaphragm secured in a casing 18 in which is mounted an electromagnet 19. The diaphragm shown in Figure 2 is of a suitable non-magnetic material such, for example, as hard rubber. At the center thereof is secured a small disk 21 of magnetic material, preferably metal, which is positioned to be attracted by the electromagnet. Variations 15 in the electric current passed through the coil of the magnet effect variations in the pull of the magnet upon the disk 21 thereby causing a vibratory movement of the disk 21, which vibrations are transmitted to the diaphragm. The disk 21 is secured to the diaphragm proper by a suitable rivet 21a 20 or the like which forms the only support for the disk 21 and the only connection between the disk 21 and the non-magnetic material of the diaphragm. The main body of the diaphragm is secured about its periphery in 25 the casing 18.

In this diaphragm of Figure 2, the central portion 20 thereof, to which the disk 21 is secured, is thin as is the central portion of the diaphragm shown in Figure 1, and this portion increases gradually in thickness in a radial direction. About the central portion 20 the diaphragm consists of a series of concentric rings 22 which are spaced radially and connected by thin web-like rings 23. 30 The thin rings 23 do not all lie in the same plane but they are preferably staggered as shown so that no two adjacent rings 23 lie in the same plane. In addition, as shown in Figure 2 and in Figure 3, it is advantageous 35 to have the heavy rings 22 increase progressively in cross-sectional area from the center outwardly. This increase in the cross-sectional area of the rings increases the difference in weight between adjacent rings. The 40 vibrations of the diaphragm shown in Figure 2 in response to sounds of various pitch are substantially as described in connection with the diaphragm of Figure 1.

Although hard rubber or the like is found 45 to be a satisfactory material for the construction of these diaphragms, it is to be understood that other materials may be employed. The diaphragms may be made conveniently by cutting away the required portions from a solid disk of material, simply cutting circular grooves in the material from opposite surfaces of the disk to form the thin web-like 50 portions or rings 17 or 23.

As many possible embodiments may be 55 made of the above invention and as many

changes might be made in the embodiment above set forth, it is to be understood that all matter hereinbefore set forth or shown in the accompanying drawings, is to be interpreted as illustrative and not in a limiting 70 sense.

We claim as our invention:

1. A sound reproducing diaphragm comprising a disk made up of a series of radially spaced concentric rings of substantial thickness in an axial direction joined together by intervening web-like rings of a thickness in an axial direction substantially less than that of said first rings. 75

2. A sound reproducing diaphragm comprising a thin central portion and about said central portion a series of spaced concentric rings which are thicker in an axial direction than is said central portion, said spaced concentric rings being joined together by thin 80 web-like rings. 85

3. A sound reproducing diaphragm comprising a disk which has a small central portion thereof gradually increasing in thickness in a radial direction from its center, a ring about said small central portion which is relatively thick in an axial direction, and spaced radially from said first thick ring a series of similar relatively thick rings spaced from each other in a radial direction and joined by rings which are relatively thin in an axial direction. 90

4. A sound reproducing diaphragm comprising a disk made up of a series of radially spaced concentric rings of substantial cross-sectional area and weight joined together by thin and web-like intervening rings, said first rings increasing progressively in cross-sectional area and weight from the central portion of said disk outwardly toward the 100 periphery. 105

5. A sound reproducing diaphragm comprising a disk made up of a series of radially spaced concentric rings of substantial thickness in an axial direction joined together by intervening web-like rings of a thickness in an axial direction substantially less than that of said first rings, the adjacent web-like rings lying in different planes. 110

6. An acoustic diaphragm comprising a disk-like member made up of radially spaced substantially concentric rings each of substantially rectangular cross-section and intervening relatively thin web-like rings joining said first-mentioned rings together. 115

7. An acoustic diaphragm comprising a disk-like member of substantial thickness in an axial direction and having pairs of concentric grooves, the grooves of each pair being on opposite sides of said member and of substantially the same diameter and separated from each other by thin web-like portions. 120

8. An acoustic diaphragm comprising a disk-like member of substantial thickness in an axial direction and having pairs of con- 125

centric grooves, the grooves of each pair being on opposite sides of said member and one groove of each pair being of greater depth than the other groove.

5 9. An acoustic diaphragm comprising a member made up of a series of spaced rings grouped about a common axis, said rings being of progressively differing diameters and having different natural periods of vibration, and means joining adjacent spaced rings, said joining means being of a character to give said rings freedom to vibrate relative to each other.

10 10. An acoustic diaphragm comprising a member made up of a series of concentric ring-like members, each of substantial mass, said rings having different natural periods of vibration and having different diameters, and means holding said rings concentrically 15 and joining said rings, said holding and joining means being of a thickness insufficient to prevent said rings to vibrate relative to each other.

11. An acoustic diaphragm comprising a member made up of a series of concentric ring-like members, each of substantial mass, said rings having different natural periods of vibration and having different diameters, and means holding said rings concentrically 20 and joining said rings, said holding and joining means being of a thickness insufficient to prevent said rings to vibrate relative to each other and extending in a general radial direction between adjacent rings.

30 35 12. An acoustic diaphragm comprising a member made up of a series of concentric ring-like members, each of substantial mass, said rings having different natural periods of vibration and having different diameters, and means holding said rings concentrically 40 and joining said rings, said holding and joining means being of a thickness insufficient to prevent said rings to vibrate relative to each other, said rings and the joining means in- 45 termediate of adjacent rings being integral.

In testimony whereof, we have signed our names to this specification this nineteenth day of May, 1926.

GEORGE G. ROCKWELL.

50 CHARLES L. WALTERS.
